HENRY G. GROS, OF OAKVILLE, CONNECTICUT, ASSIGNOR TO THE WATERBURY TOOL COMPANY, OF WATERBURY, CONNECTICUT, A CORPORATION OF CONNECTICUT

MOORING APPARATUS FOR AIRCRAFT

Application filed July 2, 1930. Serial No. 465,345.

The invention relates to mooring apparatus for air craft more particularly of the dirigible lighter than air type commonly known as air ships, and has for an object to provide a self-propelled mooring apparatus of simple construction, capable of handling the dirigible without the assistance of outside power, and without the services of a landing crew. The invention further contemplates the provision of a mooring tower or mast constructed in a novel manner to be easily and efficiently raised and lowered as required by existing conditions. Other objects will appear from the description hereinafter and the features of novelty will be pointed out in the claims.

In the accompanying drawings, which illustrate an example of the invention without defining its limits, Fig. 1 is a plan view of the novel mooring apparatus, partly in section; Fig. 2 is an elevation thereof; Fig. 3 is a detail elevation of the mooring tower, and Fig. 4 is a detail view, partly in section, of the control means.

For the purpose of illustration and description the drawings show a somewhat schematic representation of a stub-type mooring mast embodying the novel features, it being understood that the latter are not limited to this class of masts and that they may be utilized in the construction of other types of mooring masts, with equal efficiency.

In all of its forms, the mooring apparatus comprises a self-contained unit capable of handling the dirigible without the use of outside power or the services of a landing crew, and in the illustrated example, consists of a supporting frame or platform 10 of suitable construction and preferably 40 of rectangular form as shown in Fig. 1. In the example shown the platform 10 is carried by trucks, four of which, indicated as 11, are located, in suitably spaced relation, along a diagonal centre line of the platform 45 while additional trucks 12 are located at each lateral extremity of the platform 10 to support the same at these points. The trucks 11 and 12 are adapted to travel along conventional railroad tracks 13 arranged in the 50 proper relationship and predetermined di-

rection preferably so as to be level with the ground; with the arrangement set forth the platform is thus carried in diagonal relation to the tracks 13 as shown in Fig. 1. While the illustrated arrangement of running gear and position of the platform therein is a preferred one, for the reasons more fully set forth hereinafter, it is to be understood that other arrangements may be substituted if this should be desired or found advisable. In practice the tracks or rails 13 lead from within the airship shed to the landing field in a manner to constitute trackways arranged in a definite predetermined manner.

A telescopic mooring tower or mast projects upwardly from the platform 10 preferably at its central point and comprises a main section 14 suitably secured upon said platform 10, and an auxiliary section 15 in 55 slideable telescopic connection with the section 14 so as to be vertically adjustable relatively thereto to vary the height of the tower at will. The tower is preferably of rectangular cross-section, it being understood, however, that the cross-sectional shape may be other than that illustrated, without affecting the efficiency of the novel mooring apparatus. At its upper end the section 15 carries the customary ram 16 provided with the conventional cup 17 to which the dirigible may be moored in the manner to be more fully set forth hereinafter. Suitable stays 18 extending from the section 14 of the mooring tower to the platform 10 may be provided to 60 stabilize said tower for instance as shown in Fig. 2.

At a predetermined point upon the platform 10, preferably in registry with the diagonal centre line along which the trucks 11 are located, is suitably mounted an internal combustion engine 19 of conventional form and predetermined horsepower, the driving shaft 20 of which projects beyond said engine and has its free end journaled in a suitable bearing 20^a fixed upon said platform 10 as shown in Fig. 1.

The driving shaft 20 of the engine 19 is connected by means of a sprocket chain 21 and co-operating sprocket wheels with a 100

hydraulic pump 22 which in turn is connected by means of pipes 23 and branch pipes 23^a with two hydraulic motors 24; the driving shafts of the two motors 24 are connected, for instance by sprocket chains 25 and co-operating sprocket wheels with the two axles 26 of one of the trucks 11 as shown in Figs. 1 and 2. The hydraulic pump 22 and the hydraulic motors 24 with their co-operating elements are thus actuated by the engine 19 and constitute the means whereby the entire mooring apparatus is moved along the tracks 13 in the operation thereof.

The hydraulic pump 22 and the hydraulic motors 24 are preferably of the type known as the Waterbury gear, and each include a rotary cylinder barrel 27 mounted upon a shaft 28 as shown in Fig. 4. Each barrel 27 has formed therein a plurality of cylinders 29 which are parallel with the shaft 28 and accommodate pistons 30 arranged to be reciprocated therein and connected by means of piston rods 31 with a swash plate 32 mounted for rotation in a tilting box 33. In accordance with the customary construction of the Waterbury type gearing, the tilting boxes of the motors 24 may be held at a fixed inclination to the shafts on which they are mounted, and which in the instant case, are connected by the sprocket chains 25 with the axles 26, while the tilting box 33 of the pump 22 is mounted on the shaft 28 so as to be capable of adjustment to different angles of inclination whereby the speed of the pump 22 and consequently the speed of the motors 24 may be varied at will. That is to say the stroke of the pistons 30 and therefore the amount of fluid delivered by the pump in each rotation of the barrel 32 through the pipes 23 and 23^a to the motors 24 to vary the speed of the latter, is governed by the inclination of the swash plate 32 to which the pistons 31 are connected. In all other respects the motors 24 may be of the same construction and arrangement as the pump 22 illustrated in Fig. 4.

For the purpose of selectively adjusting the swash plate 32 suitable means is provided and, in the present instance is located upon a control platform 34 which constitutes a control station from which the mooring officer may exercise the required control of the mooring apparatus; in some instances a second control station may be provided on said platform 10 at the other side of the mooring tower, in order to provide dual controls. In the illustrated example the control means comprises a shaft 35 journaled in an upright support 36 mounted on the platform 34 and provided at its upper end with a hand wheel 37 or its equivalent to facilitate the control operations; the arrangement is such that the shaft 35 is free to rotate about its axis but is held against lengthwise movement. The

shaft 35 is connected with an internally threaded nut 38 rotatably mounted in the casing of the pump 22 for the accommodation of the externally threaded control shaft 39 on which is swivelled a vertically slidable bearing 40; the latter is fitted in a bifurcated lug 41 which projects from the tilting box 33 as shown in Fig. 4.

The driving shaft 20 of the motor or engine 19 is further connected, by means of a sprocket chain 42 and co-operating sprocket wheels or equivalent means with a hydraulic pump 43 from which pipes 44 lead to pipes 45 which in turn are connected with two hydraulic motors 46 located at diametrically opposite sides of the mooring tower as shown in Fig. 1. The pump 43 and the motors 46 may be, and preferably are, of the same type, construction and operation as the previously described pump 22 and motors 24 and the description of the latter accordingly applies also to the pump 43 and motors 46.

The motors 46 are operatively connected with the drums 47 of two hoists located in proximity to the mooring tower upon opposite sides thereof as shown in Fig. 1; the connection between the motors 46 and drums 47 is preferably effected by means of suitable worm gearing 48 which itself is irreversible except by the action of the motors 46 and thus acts as a lock to prevent the section 15 of the mooring tower from being unintentionally shifted relatively to the section 14 thereof. Hoisting cables 49 pass from the drums 47 to and over pulleys 50 rotatably supported at the upper end of the section 14 of the mooring tower and have their ends secured at 51 to the lower end of the section 15 of said tower. Corresponding cables 52 have their ends attached at 53 to the lower end of the section 15 and pass downwardly therefrom over pulleys 54 journaled upon the platform 10 and to the drums 47 in reverse relation to the cables 49. The arrangement is such that when the cables 49 are being wound up on the drums 47 the cables 52 will be unwound therefrom and vice versa, the purpose of the mechanism being to enable the section 15 of the mooring tower to be raised and lowered relatively to the section 14 to thereby vary the height of the mooring tower at will.

In addition to the parts so far described the novel apparatus includes another hydraulic pump 55 operatively connected by means of a sprocket chain 56 and co-operating sprocket wheels or their equivalent with the driving shaft 20 of the engine 19. The pump 55, which is suitably mounted on the platform 10, is connected by means of pipes 57 with a hydraulic motor 58 carried at a predetermined point on the platform 10 preferably in registry with the diagonal

centre line thereof, for instance as shown in Fig. 1. It will be understood that the hydraulic pump 55 and motor 58 are of the same general construction and operation as those previously described herein. The motor 58 is connected by suitable gearing 59 with the drum 60 of a main cable winch 61 fixed upon the platform 10 and serving to operate the main cable 62 whereby the air ship is hauled in or pulled to the mooring tower. The cable 62 passes from the drum 60 over a sheave 63 and a pulley 64 up through the centre of the mooring tower and ram 16 from which said cable passes through the cup 17 to the mooring cone 65 of the airship 66, to which it is secured. Preferably the sheave 63 is slidably mounted upon a shaft 67 journalled in the winch 61, said sheave 63 being movable lengthwise of the shaft 67 by means of a block 68 operated by a spirally channelled shaft 69 of conventional type operatively connected with the gearing 59 to properly lay the cable 62 on the drum 60. An auxiliary drum 70 is journalled in suitable bearings on the platform 10 in proximity to the main drum 60 and is arranged to be operatively connected with the motor 58 at will or when required by means of a suitable clutch 71. The purpose of this auxiliary drum 70 is to operate the cable 72 which is connected with the airship 66 and serves to bring the latter into parallel relation to the tracks 13 in a cross-hangar wind.

To control the yaw of the airship two yaw cable winches 73 and 74 are located upon the platform 10 at opposite sides of the mooring tower as shown in Fig. 1, said winches including drums 75 for the accommodation of the yaw cables 76 and 77 respectively; the latter pass between pulleys 78 suitably mounted upon the platform 10 and over pulleys 79 fastened at predetermined points alongside of the tracks 13, to the airship 66 to which said cables 76 and 77 may be fastened in any conventional manner. The drums 75 are connected, for instance by means of sprocket chains and sprockets 80 or equivalent devices with hydraulic motors 81 of the same kind referred to hereinbefore, said motors 81 in turn being connected by pipes 82 with a single hydraulic pump 83 of the same type as mentioned above, said pump 83 accordingly being common to both motors 81; the pump 83 itself is operatively connected with the driving shaft 20 of the engine 19 for instance by means of a sprocket chain and sprockets 84 or their equivalent and is controlled to vary the speed of the motors 81 by means of a handwheel 85 and associated elements corresponding to the handwheel 37 and its co-operating parts. The handwheel 85 is located upon the control plat-

form 34 within easy reach of the mooring officer.

It will be understood that controlling means such as described with respect to the pumps 22 and 83 may also be provided for controlling the hydraulic pumps 43 and 55 likewise may include handwheels similar to the handwheels 37 and 85 and correspondingly located upon the control platform 34 within easy reach of the mooring officer.

For the purpose of supplying current to electric lights which may be suitably distributed over the apparatus, an electric generator 86 may be operatively connected with the driving shaft 20 of the engine 19 so as to be driven thereby.

When it is desired to use the mooring apparatus the engine 19 is started, it being understood that the swash plates of the various hydraulic pumps occupy neutral positions so that no fluid is delivered to any of the hydraulic motors which accordingly are idle and transmit no power. If the apparatus is not already in the desired location the handwheel 37 is actuated to adjust the tilting box 33 and with it the swash plate 32 of the pump 22 so that the pistons 30 are caused to deliver fluid to both the motors 24. The latter accordingly transmit power by means of the sprocket chains 25 or their equivalent to the axles 26 of two of the trucks 11 and accordingly propel the apparatus along the rails 13; the direction and speed of travel may be controlled by suitably actuating the handwheel 37. When the desired location has been reached the handwheel 37 is operated to return the swash plate 32 to its neutral position and to thereby stop the operation of the hydraulic motors 24.

To moor the airship 66 to the mast, the main cable 62 is attached to the cone 65 at the nose of the airship and the proper control mechanism is operated to adjust the swash plate of the hydraulic pump 55 to an inclined position; this brings about an actuation of the pump 58 and results in a rotation of the drum 60 whereby the cable 62 is wound thereon. The airship 66 is thus gradually drawn toward the mooring tower and its mooring ball 65 is finally seated in the cup 17 in the customary manner. If for any reason, such as a cross-hanger wind, it should be necessary to bring the airship 66 parallel to the tracks 13 during the hauling-in operation, this may be done by operating the clutch 71 to connect the auxiliary drum 70 with the motor 58. Under such conditions the cable 72 will be operated to bring the airship 66 into parallel relation to the tracks 13 and to hold it there. The advantages of this arrangement are that control of the cable 72 in the aforesaid maneuver may be effected from a

centralized control station on the apparatus, and that the speed of cable haul-in can be instantly varied or even reversed which is in contrast to the method of effecting speed changes in mechanical gearing such as is included in winches which are employed in existing mooring mast constructions, using gearing or similar devices.

When the airship 66 has been thus moored to the mast the handwheel 37 may be actuated to properly adjust the swash plate 32 of the pump 22 and thereby bring about an operation of the two motors 24 whereby power is transmitted to the wheels of two of the trucks 11 to propel the mooring apparatus along the tracks 13. The airship 66 may thus be easily moved into the hangar, the self-contained apparatus generally being used to push the airship into said hangar.

The use of the hydraulic pump and motors for propelling the apparatus positively insures the starting and stopping thereof without shock, which are invaluable advantages when handling airships attached to a rigid element such as a mast. Furthermore the speed of travel of the apparatus on the rails 13 can be accurately adjusted and varied to suit any conditions, and the start may be made at a speed which is hardly perceptible, after which said speed may be gradually accelerated until the desired rate has been reached. In the same way, the speed of travel can be gradually decelerated when the airship nears its intended position in the hangar, and the apparatus can be brought to a stop without shock.

To control the yaw of the airship during mooring thereof the proper handwheel at the control station 34 is operated to adjust the swash plate of the hydraulic pump 83 and cause the latter to operate the two motors 81 and the co-operating drums 75. The cables 76 and 77 will accordingly be hauled in by being gradually wound up on the drums 75. As long as both cables 76 and 77 are taut and the tension is equal both drums 75 will exert the same torque and the two cables 76 and 77 will be hauled in at the same rate of speed. Should the tension on one of the cables 76 and 77 be increased and decreased on the other due to the yaw of the ship, the hydraulic motors 81 will be caused to automatically slow down the winding speed of the one drum 75 and increase the winding speed of the other drum 75 until such time as the tension on both of the cables 76 and 77 again becomes equalized whereupon both drums 75 will again rotate at the same winding speed. The differential action of the two motors 81 provides an automatic take-up for the yaw cables as the airship gradually approaches the mooring mast and thereby efficiently prevents side sway of the airship when being hauled in.

If for any reason it should become necessary or desirable to vary the height of the mooring tower it is simply necessary to actuate the handwheel which controls the hydraulic pump 43 to cause it to operate the two motors 46 and winches 48. In the raising of the tower the drums 47 are rotated in a direction to wind up the cables 49 and to coincidentally unwind the cables 52. A lifting action is accordingly developed by the cables 49 on the section 15 which raises the latter to the desired extent relatively to the section 14 of the mooring tower; in lowering the section 15 the drums 47 are rotated in the reverse direction to wind up the cables 52 and to unwind the cables 49. From the above it will be clear that the height of the mooring tower may be selectively adjusted to any extent within its range which is sufficient to cover any conditions which may arise. The cables 52, in addition to their other functions, serve to counteract and prevent any unintentional raising of the section 15 under the pull of the airship or any other forces developed thereby; it will be obvious that as the drums 47 are operatively connected with the hydraulic motors 48 by means of worm gearing which is irreversible excepting by the action of said motors, the section 15 will be securely locked at any height above the section 14 of the mooring tower.

The novel apparatus provides a self-propelled airship mooring mast comprising an entirely self-contained unit which includes the necessary power for the main haul-in cable, the yaw winches, means for raising and lowering the mooring tower to suit the conditions existing at the time of landing, and means whereby the mooring mast and airship may be moved into the shed or elsewhere as required. The apparatus is capable of handling the dirigible or other airship without outside power and without the necessity for any landing crew, and without imparting undesirable shocks to the airship being handled. The tracks on which the apparatus is arranged to travel are located in predetermined arrangement leading from within the shed or hangar out to the landing field. The airship may be brought to the apparatus and moored to the tower as above set forth and then, whenever conditions are suitable, may if desired be moved by the self-propelled apparatus into the shed. The tracks provide an even uniform pathway for the apparatus and eliminate the irregular, jerky movements which would be imparted to the airship if the apparatus travelled directly upon uneven ground; said tracks also reduce the power required to move the mooring mast either alone or with the airship moored thereto. In case the mooring takes place in winds of unusual velocity suitable means may be pro-

vided for anchoring the apparatus to the track preliminary to mooring, in order to prevent the pull of the airship from unintentionally moving the apparatus. The entire control of the apparatus and the operation of mooring the airship thereto and moving it into the hangar may be accomplished by one mooring officer who may direct the operation from one centralized point represented by the control platform 34.

With the illustrated arrangement the weight is concentrated along the diagonal centre line of the platform 10 and four of the carrying trucks are located along this line, with two additional trucks at opposite lateral extremities of the platform 10 for supporting these points. The result is an evenly balanced construction easy to control and efficient in operation.

The mooring mast of rectangular cross-section included in the apparatus provides a rigid mooring device, with the upper section thereof capable of being raised and lowered with a minimum of mechanical effort. The use of the hydraulic, variable speed pumps and motors provides a very close control of speed, and a high starting torque, which is of special advantage in connection with the propulsion of the apparatus, in that it is necessary to start and stop such large units as exemplified by the moored airships, with considerable care and accuracy, in order to avoid damage thereto.

Various changes in the specific form shown and described may be made within the scope of the claims without departing from the spirit of the invention.

I claim:

1. In a mooring apparatus for airships, the combination of a track, a platform arranged to travel on said track, an upwardly extensible mooring mast carried by said platform, a plurality of hydraulic variable speed gears for raising and lowering said mast at will, and for moving said platform along said track, and a single engine whereby all of said hydraulic gears are operated.

2. In a mooring apparatus for airships, the combination of a track system, a platform carried by trucks arranged to travel on said track system, a mooring mast mounted on said platform, a cable winch and haul-in cable arranged to haul the airship to said mast, yaw winches and cables for controlling the side sway of said airship, hydraulic variable speed gears for actuating said winches, additional hydraulic variable speed gears connected with at least one of said trucks for propelling said platform over said track system, and a single engine on said platform common to all of said hydraulic gears for operating the same.

3. In a mooring apparatus for airships, the combination of a track system, a platform carried by trucks arranged to travel

on said track system, a mooring mast mounted on said platform, a cable winch and haul-in cable arranged to haul the airship to said mast, yaw winches and cables for controlling the side sway of said airship, hydraulic variable speed gears for actuating said winches, additional hydraulic variable speed gears connected with at least one of said trucks for propelling said platform over said track system, a single engine on said platform common to all of said hydraulic gears for operating the same, a control platform on said platform, and controlling devices on said platform whereby the operation of said hydraulic gears is controlled.

4. In a mooring apparatus for airships, the combination of a track system, a platform carried by trucks arranged to travel on said track system, a mooring mast mounted on said platform, a cable winch and haul-in cable arranged to haul the airship to said mast, yaw winches and cables for controlling the side sway of said airship, hydraulic variable speed gears for actuating said winches, additional hydraulic variable speed gears connected with at least one of said trucks for propelling said platform over said track system, a single engine on said platform common to all of said hydraulic gears for operating the same, an auxiliary drum and cable for bringing the airship into parallel relation to said track system, and means whereby said auxiliary drum may be operatively connected at will with the hydraulic gear whereby the cable winch and haul-in cable are operated.

5. In a mooring apparatus for airships, the combination of a track system, a rectangular platform located in diagonal relation to the tracks of said system, a series of trucks for supporting said platform along a diagonal centre line thereof on said track system, additional trucks at the lateral extremities of said platform for supporting the latter at these points on said track system, a mooring mast carried by said platform at approximately its central point, a cable winch and haul-in cable carried by said platform in registry with said diagonal centre line for hauling the airship to the mast, hydraulic variable speed gear located on said platform in approximate registry with said centre line for operating said winch and haul-in cable, hydraulic variable speed gear located on said platform in approximate registry with said centre line and connected with at least one truck of said series for propelling the platform over said track system, and a single engine carried by said platform in registry with said centre line for operating all of said hydraulic gears.

6. In a mooring apparatus for airships, the combination of a track system, a platform arranged to travel over said system,

an upwardly extensible mooring mast rectangular cross-section mounted on said platform, a plurality of hydraulic variable speed gears on said platform for propelling the latter over said track system, and for raising and lowering said mast, and a single engine on said platform for operating all of said hydraulic gears.

7. In a mooring apparatus for airships, the combination of a track system, a platform arranged to travel over said system, an upwardly extensible mooring mast rectangular cross-section mounted on said platform, in registering diagonal relation therewith, a haul-in cable for hauling the airship to the mast, cables for raising and lowering said mast, yaw cables for controlling the yaw of said airship, a plurality of winches on said platform for independently operating said cables, a plurality of hydraulic variable speed gears for operating said winches, and a single engine on said platform for operating all of said hydraulic speed gears.

8. In a self-propelled mooring apparatus for airships, the combination of a traveling platform, an extensible mooring mast on said platform, comprising a fixed section and a vertically movable section telescopically connected with said fixed section, two winding drums on said platform, opposed cables extending from each of said drums and connected with said movable section in opposed relation, two hydraulic motors on said platform, worm-gearing connecting each motor with one of said drums, said worm-gearing being irreversible except by the action of said motors, a single hydraulic variable speed pump on said platform controlling and operating both of said motors, and means on said platform for operating said pump.

In testimony whereof I have hereunto set my hand.

HENRY G. GROS.
